UNITED STATES PATENT OFFICE.

JOSEPH L. CHAPMAN, OF PHILADELPHIA, PENNSYLVANIA.

RAILROAD-TIE AND FASTENING.

SPECIFICATION forming part of Letters Patent No. 283,076, dated August 14, 1883.

Application filed September 25, 1882. (No model.)

To all whom it may concern:

Be it known that I, JOSEPH L. CHAPMAN, of Philadelphia, State of Pennsylvania, have invented a new and useful Improvement in Railroad-Ties and the Mode of Securing the Rails of the Tie; and I do hereby declare the following to be a full, clear, and exact description of the same, reference being had to the accompanying drawings, making part hereof.

10 The nature of my invention will be fully apparent from the following specification and claims.

In the drawings, Figure 1 is a cross-sectional view of the rail and connections and part of the channel-bar tie on the line X Y of Fig. 3. In this view the channel is uppermost, while the plain face of the bar is upon the ground; Fig. 2, a plan view of the form of construction shown in Fig. 1; Fig. 3, a cross-sectional view 15 on the line V W of Fig. 2; Fig. 4, an outline side view of a tie formed of two plain upper and lower plates of iron held apart by interposed blocks secured between them, also showing the rails in place, with their fastenings. Fig. 5 is a detached view of the clamp C, showing its lower side, illustrating also the form of the heel or lug G'', which projects down into the hole F of the bed-plate E, and also the shoulder G', which sets up against the edge of 20 the base of the rail.

Though the tie may be made in the various forms shown, I shall confine my description more to the form shown in Figs. 1, 2, and 3, where the channel-bar tie is shown with its 25 plain face down, adapted to be set upon the ground with the channeled side uppermost.

A is the tie, formed of channel-iron.

B is the rail.

C C' are block-clamps for holding the rail 30 down upon the bed-plate E, which bed-plate is secured to the web of the channel bar or tie by means of rivets E' E''. (See Figs. 2 and 3.) A bolt, D, having a T-shaped head, G, secures the clamp in place and holds the rail B down 35 upon the bed-plate E. The bolt D has a screw-threaded end, upon which is set the screw-nut D'.

F is an opening into the bed-plate E, terminating in a narrow slot, F'. (See Fig. 2.) A 40 hollow chamber is thus formed beneath the slot F' to receive the head of the bolt, which chamber is protected from the entry of dirt or

earth from the ground beneath by the interposed tie, upon which the bed-plate E rests. The hollow chamber is thus prevented from 45 clogging up, whereby the head of the bolt is enabled to freely enter it. The T-head of the bolt is inserted into this opening F, and the bolt is then pushed toward the rail. The T-shaped head will thus be forced under the 50 lower edges of the narrow slot F', while the neck of the bolt close to the head will fit closely in this slot F', the screw-threaded end of the bolt projecting upward out of the slot. The clamp C, being pierced with holes to receive the bolt, is pushed down over this screw-threaded end of the bolt, the heel G'', Fig. 2, of the clamp setting down and fitting closely 55 into the opening F, (see Fig. 1,) while the side edges of the clamp—the latter being wider 60 than this opening—will overlap the opening and enable the side edges of the rear end of the clamp to rest down upon the bed-plate E. As the screw-threaded end of the bolt D projects up through the clamp, (see Figs. 1 and 3,) 65 screw-nut D' is set upon the bolt end, thus drawing the clamp tightly down upon the rail, as shown in Fig. 1. A description of the mode of securing one of these clamps answers 70 for all, as they are all duplicates.

H is a thin layer of rubber, felt, leather, or other suitable packing, designed to remove, as much as possible, the effects of the concussion of passing trains upon the iron connections of the tie and rail and to deaden the sound. 75

While I have described the bolt D as being T-headed, it may be round-headed, or a common square-headed bolt, the head constituting flanges or shoulders to hold the bolt down when passed into the slot F'. 80

I make the bed-plate E of cast iron or steel, the holes for rivets E' E'' and openings F and slots F', with a space beneath the slot and opening to receive the bolt-head, being cast in the bed-plate near each end, as shown, when 85 the bed-plate is formed. The holes in the tie to receive the rivets E' are punched through the tie.

Although I have described channel-iron as being the best adapted for my purpose, I can, 90 if it is desired, use a plain flat bar of iron instead of the channel-iron; but channel-iron is preferable in the position shown in Figs. 1, 2, and 3, as the flanges of the channel-iron form

side supports or braces to hold the bed-plates in place. The channel-iron also makes a stronger bar, and obviates the danger of the tie bending in the middle, as the flanges form 5 side braces and prevent such bending.

These ties are all cut into suitable lengths and punched with holes to receive the rivets at the mill where they are made. This being done by measurement or gage, the ties are all 10 alike. The bed-plates are all cast, and holes for the rivets are cast in them at the foundry where they are made, so as to correspond exactly with the punched holes in the ties. The bed-plate and ties are thus ready to be put together 15 immediately on being completed, and to hold the rails at a proper distance apart, according to the gage desired. Thus the trouble and delay incident to laying railroad-tracks and keeping them apart at the proper 20 gage are avoided, as the rails cannot help being held apart at the proper gage immediately on being laid upon my ties. A small hole of opening or channel, I, is cast in the lower face of the bed-plate, to permit the escape of water 25 which may gather between the rails.

While the clamp C impinges with that edge next to the rail down upon the base of the rail, a small shoulder, G', (see Fig. 5,) sets against the edge of the base-flange of the rail, so as to 30 clasp it closely and prevent the rail from spreading. By the use of differently-sized clamps C, rails of varying widths at their bases can be employed.

It will be observed that while each bed- 35 plate E is provided with openings to receive

bolts and fastening-clamps and means for securing it to the underlying tie, yet its upper and lower surfaces are perfectly plain and free from projections, by which means the bed-plates, in being shipped from place to place 40 in numbers, will pack closely and occupy the smallest possible space.

What I claim as new is—

1. The combination of a railroad-tie, A, bed-plates E, set upon the upper surface of the tie, and provided with openings F and slots F', hollow beneath, and protected from entry of earth from the ground by the interposed tie beneath the hollow chamber thus formed, bolts D, and clamps C, the bolt-heads being 45 adapted to be passed into said openings F, and into the protected hollow chamber beneath the slots F', whereby the bolts will project up through the slots and clamp C, the whole being held in place by the nuts D, substantially 50 as described.

2. The bed-plates E, having openings F and slots F', hollow beneath, and adapted to be clamped to the rail and secured to an underlying railroad-tie, said bed-plates being plain 55 or free from projections on their upper and lower surfaces, whereby they can be packed closely and take up small space while being shipped in numbers from place to place, substantially as described.

JOSEPH L. CHAPMAN.
